Reinhart Koch
BY
Victor J. Evans, ATTORNEY.

UNITED STATES PATENT OFFICE.

REINHART KOCH, OF NEW YORK, N. Y.

BOTTLE-CLOSURE.

No. 873,869.

Specification of Letters Patent.

Patented Dec. 17, 1907.

Application filed December 12, 1906. Serial No. 347,527.

To all whom it may concern:

Be it known that I, REINHART KOCH, a citizen of the United States, residing at New York city, in the county of New York and State of New York, have invented new and useful Improvements in Bottle-Closures, of which the following is a specification.

My invention relates to bottle closures and more particularly to that class which employs a cap of metal or similar material which is placed over the mouth of the bottle and to which pressure is applied and the cap is pressed upon the bead at the mouth of the bottle and thereby retained in its place, as will be explained more fully in the following specification, set forth in the appended claims and illustrated in the accompanying drawings where it will be seen that like reference characters are used to designate the same parts in the several figures.

Figure 1 is a perspective view of the neck of a bottle showing my improved cap applied thereto. Fig. 2 is a side elevation the ring being shown partially removed. Fig. 3 is a vertical sectional view of the neck of the bottle showing the closure applied and ready for locking in its place. Fig. 4 is a similar view with the closure locked in its position. Figs. 5 and 6 are views of the blanks used in the construction of the parts of the invention.

This invention is adapted to be applied to bottles to contain beverages or liquids which require air tight sealing and is used in connection with a cork or other means for preventing the entrance of air or the exit of gas. To accomplish this the cap 10 is made of such a shape as to fit down over the mouth of the bottle and fit closely around the bead 11 at the same time to contain the cork disk 12.

The cap 10 has depending from its vertical flange the lips 13 which are shown to be four in number but it is obvious that they may be of greater or less number, and one of them, the lip 14, is elongated and perforated to receive some tool for removing the cap.

At the point where the lips join the cap they are bent inward and have an angular formation 15 which is adapted to be sprung under the lower side of the bead 11. This however, is not sufficient to secure the cap to the bottle and to further lock and fasten the cap upon the neck a ring 16 made of sheet metal or similar material and having an inward projecting flange 17 to strengthen same and give it more body is used. When

this ring 16 is forced down upon the cap 10 as shown in Fig. 4 it not only forces in the lips 13 to a closer contact with the neck of the bottle but holds them against outward movement or expansion and effectually prevents the release of the cap 10. It will be borne in mind that the ring 16 fits the cap closely and it may be necessary to use some force to drive it to its final position.

When it is desired to remove this cap a hook or some tool is inserted in the perforation 18 of the elongated lip 14 and pulled upward which will first have the effect of removing the ring 16, thus releasing the lips and finally the strain will remove the cap 10.

The blanks shown in Fig. 5 and 6 illustrate the simplicity of construction of this device and shows how they will be readily formed after being cut from the sheet metal.

It is obvious that I do not confine myself to the exact construction illustrated and above described but may vary the shape and proportions of the various parts if it is found necessary.

What I claim as new and desire to secure by Letters Patent is:

1. In a bottle closure the combination with a cap having dependent lips adapted to engage the neck of the bottle, and an elongated lip for releasing the cap and means adapted to fit about the cap and the lips when they engage the neck to lock them thereon.

2. In a bottle closure the combination with a bottle provided with a head, of a cap carrying a cork or similar sealing means and having depending lips with angles to engage the bead, a ring adapted to fit about the cap and force and hold the lips beneath the bead, and means for removing the ring and the cap.

3. The combination with a bottle provided with a bead, of a cap provided with means adapted to engage the bead to secure the cap in applied position, a member adapted to retain said means in engagement with the bead, and means by which said member may be displaced and the cap removed.

In testimony whereof I affix my signature in presence of two witnesses.

REINHART KOCH.
